DECK LAYING TOOL

James I. Kushima, Ewa, Territory of Hawaii

Application September 7, 1938, Serial No. 228,833

3 Claims. (Cl. 254—11)

This invention relates to deck laying tools and more particularly to a backing block to facilitate the wedging together of the individual decking strips, preparatory to fastening them to a steel 5 deck or angle iron supports.

In the laying of wood decks it has been the practice to employ a tapered steel pin or deck bolt inserted in the bolt hole of the deck supports as a backing for the wedge. These methods are objectional for the reasons that the pins or bolts being 10 of small diameter do not provide sufficient bearing surface for the wedge, further they tend to deform the bolt hole into which they are driven and if the deck plate is thin and the pin is driven 15 in tightly they are difficult to remove.

It is an object of the present invention to provide a device which will overcome the objections of the present practice being provided with a broad bearing surface for the wedge and secured 20 to the deck plate or angle iron support so as to be rigid and not deform the bolt hole to which it is attached.

A further object of the invention resides in providing a device of the above-mentioned character which is simple and durable in construction, 25 reliable and efficient in operation and inexpensive to manufacture.

Other objects and advantages of the invention will be apparent during the course of the following description.

In the accompanying drawing, forming a part of this specification and in which like numerals are employed to designate like parts throughout the same,

35 Fig. 1 is a top plan view of the tool in use,

Fig. 2 is a side elevation of the same, partly in vertical section, and,

Fig. 3 is a fragmentary perspective view of an 40 angle iron support showing the attaching bolt inserted in one of the bolt holes.

In the drawing, wherein for the purpose of illustration I have shown a preferred embodiment of my invention, the numeral 5 denotes a steel casting of right angular shape to provide a broad 45 horizontal base 6 and relatively wide vertical face 7. A vertical post 8 is cast integral with the rear of the face 7 and extending between the post and base 6 are reinforcing webs 9. The post 8 has a longitudinal bore 10 which extends through the base 6 and the upper end 11 of the bore is relatively larger in diameter than the lower end. An attaching bolt 12 is slidably fitted in the bore 10 having an enlarged upper end 13 provided with 55 screw threads 14 which have threaded engage-

ment with the head 15 formed integral with one end of a handle 16 by means of which the bolt 12 is adjusted. A nut 17 threaded on the upper end of the bolt above the head 15 serves to lock the bolt in its adjusted position. The lower end of the 5 bolt 12 is bent to form an angular projection 18 adapted to engage in one of the bolt holes 19 in the angle iron support 20 or steel deck to secure the block for backing the wedge 21 which is driven between the face 7 of the block and the deck 10 strips 22.

In use, the tool is placed on the angle iron support 20 with its face 7 parallel with the deck strips 22 and is then tilted forwardly sufficiently to permit the angular projection 18 to enter one of the 15 holes 19, it being observed that the bolt 12 is turned so that the projection 18 points toward the vertical face 7. With the projection 18 engaged in the bolt hole the base 6 rests level on the support 20 and by turning the handle 16, the bolt 12 20 is raised to bring the projection into loose contact with the underside of the support thus firmly anchoring the block in place. After adjustment of the bolt 12 the nut 17 is tightened to lock the bolt in its adjusted position. After initial adjustment of the bolt 12 to a given thickness of support 25 the tool may be readily set in position or removed by tilting the same forward to insert or remove the angular projection from the bolt hole. When affixed to the support the wedge 21 is inserted 30 between the face 7 and deck strips 22 and upon applying force to the wedge any tendency to lift or displace the block will be counteracted by the projection 18 engaged in the bolt hole coming in contact with the underside of the support. 35

It is to be understood that the form of my invention herein shown and described is to be taken as a preferred example of the same and that certain changes in the shape, size and arrangement of the parts may be made without 40 departing from the spirit of the invention or scope of the claims.

Having thus described my invention, I claim:

1. A wedge backing block for laying decking strips comprising a block having a horizontal base 45 and vertical face, said vertical face having a longitudinal bore extending through the base of said block, an attaching bolt slidably mounted in the bore of said face having its lower end projecting below said base and bent to form an angular projection adapted to releasably engage in a bolt hole of the decking support, a handle having a head threaded on the upper end of said bolt for adjusting said bolt vertically and a nut 50 threaded on the upper end of said bolt above the 55

- head of the handle for securing said bolt in its adjusted position.
2. A wedge backing block for laying decking strips comprising an angular casting having a horizontal base and vertical face, reinforcing webs between the base and vertical face, a central vertical post adjacent the vertical face having a counter-sunk bore extending therethrough, an attaching bolt slidably mounted in the bore of said post having an enlarged upper end provided with screw threads and its lower end extended through said base and bent to form an angular projection adapted to engage in a bolt hole of the decking support, a handle having a head in threaded engagement with said bolt for adjusting the same vertically and a lock nut threaded on the upper

end of said bolt for securing the same in its adjusted position.

3. A wedge backing block for laying decking strips comprising a block having a horizontal base and vertical face, said vertical face having a longitudinal bore extending through the base of said block, an attaching bolt mounted in the bore of said face having its lower end projecting below said base and bent to form an angular projection adapted to releasably engage in a bolt hole of the 10 decking support and means for adjusting said bolt vertically to regulate the extent to which the angular projection extends below the base of said block.

JAMES I. KUSHIMA. 15
